UNITED STATES PATENT OFFICE.

GUSTAV DIECKMANN, OF SAN FRANCISCO, CALIFORNIA.

FOLDING BOX.

1,156,673.

Specification of Letters Patent. **Patented Oct. 12, 1915.**

Application filed July 14, 1914. Serial No. 850,926.

To all whom it may concern:

Be it known that I, GUSTAV DIECKMANN, a citizen of the United States, residing in the city and county of San Francisco and State 5 of California, have invented new and useful Improvements in Folding Boxes, of which the following is a specification.

This invention relates to a folding box or crate for the transportation of eggs, fruits, 10 vegetables and the like.

The principal object of the invention is to provide a box of the class described of simple and durable construction which, when emptied of its contents, may be quickly and 15 easily folded in small compass for return shipment.

Another object of the invention is to provide a space between the folding sections and bottom of the box in which such parts as 20 cover sections, filler parts, and the like, may be placed for return shipment; and to provide means for automatically retaining the folded sections in closed position when folded.

25 Another object of the invention is to provide a simple form of retaining means for securing the parts together in the erected position which cannot possibly be injured or displaced during shipment in either direction.

The invention consists of the parts and the construction and combination of parts as hereinafter more fully described and claimed, having reference to the accompanying 30 drawings, in which—

Figure 1 is a perspective view of the folding box. Fig. 2 is a cross section of same, showing the end and side sections in the folded position. Fig. 3 is a detail section, 40 showing one of the retaining latches. Fig. 4 is a perspective view of the latch housing. Fig. 5 is a detail cross section of a side and end section, showing the tongue and groove construction.

45 The bottom A of the box is preferably solid and has secured thereto stationary end sections 2 and 3 and side sections 4 and 5 of similar nature. The end sections 2 and 3 are of equal height, while the height of the side 50 sections 4 and 5 varies for purposes herein-after to be described.

2^a and 3^a are foldable end sections which are secured to the sections 2 and 3 by hinges 6, and 4^a and 5^a are foldable side sections which are secured to the sections 4 and 5 by 55 hinges 7. The outer ends of the foldable side sections are provided with tongues or projections 8 which are adapted to project into grooves 9 formed on the sides of the foldable end sections. The tongue and 60 groove construction provided serves as a means for holding the several sections in perfect alinement, and, furthermore, relieves the securing latches, hereinafter to be described, from lateral thrust or side play. 65

The securing latches are constructed and applied in the following manner: The outer corners of the end sections are first beveled off, as shown at 10, Fig. 3, a spring catch 11 is then applied and secured by a screw 12. 70 A channel shaped bracket or reinforcing member 13 is then placed over the spring latch and secured in position by means of screws or nails 14. The channel shaped member 13 is provided as a housing for the 75 latch to protect it from possible knocks and injury and also supports it against any side strains to which it might be submitted.

15 is a latch, and this is secured by screws 16 to the side panels, as shown in Figs. 1 80 and 3. The inner end of the latch is downwardly turned, as at 17, and is thus in position to be thrown into engagement with the catch 11. By referring to Fig. 3, it will be seen that the hook end 17 of the latch 15 85 does not project beyond the tongue projection 8 formed on the side. This is of great importance as it would otherwise be subject to injury for reasons hereinafter to be described. 90

Secured at one end, as at 18, in the stationary side sections 4 and 5 are springs 19, the other ends of which are secured, as at 20, in the foldable side sections 4^a and 5^a. The action of these springs will be as follows: 95 When folding the box for return shipment, it is only necessary to depress the catches 11; openings 13^a being formed in the latch housing through which the fingers are inserted for this purpose. Depression of the 100 catches 11 releases the hooked ends of the latches 15 and will, therefore, permit the

side sections to be moved out of engagement with the end sections 2^a and 3^a. The end sections are then folded inwardly in the direction of arrows *a* and the side sections 4^a 5 and 5^a may then be released and will be automatically folded by the action of the springs 19 and will, furthermore, be retained in this position, by reason of the spring tension, during reshipment without any other means. The tongue projections 8, formed on the ends of the side sections, form a spacing between each foldable section which holds the hook ends of the latches 15 out of engagement with any surface. They are thus protected against injury and, being turned inwardly, as shown, are furthermore prevented from catching or hooking into the other articles with which they may be in contact.

20 The stationary end sections 2 and 3 form a space between the bottom and the foldable sections, into which such parts as sectional covers, box fillers for eggs, and the like, may be inserted, when the box is folded and re-shipped, and the variation in height between the stationary side sections 4 and 5 is provided for the purpose of permitting the section 5^a to assume a straight horizontal position with relation to the foldable side section 4^a. A rectangular or even shaped package is thus secured, when the parts are folded, which can be easily handled.

The mounting and construction of the retaining catches 11 prevent these from injury. The depth of the beveled notch 10 permits each catch 11 to be depressed downwardly only a limited distance, and this distance is so limited that the spring action of the catch cannot possibly be injured. The 40 housings 13 furthermore prevent the spring catches from injury, such as might be received from bumps and knocks, and also act as corner protectors or braces which strengthen the parts. A box constructed as shown is simple and compact in construction and may be quickly folded or erected, as the case may be, without any exertion on the part of the shipper. The springs 19 form an automatic means by which the foldable sections are held in closed position, when folded, and entirely eliminates such applications as ropes or locks for holding the parts together during reshipment.

Having thus described my invention, what I claim and desire to secure by Letters Patent is—

1. In a folding box, a bottom having rigid side and end sections and hinged side and end sections on the respective rigid side and end sections, and springs for the adjacent rigid and hinged side sections each composed of a rod having right angular oppositely disposed ends, the body of the rod be-

ing interposed between the adjacent edges of the rigid and hinged side sections and the 65 said rod ends being secured to the respective rigid and hinged side sections.

2. In a folding box, hinged side and end sections, an inverted U-shaped bracket secured to the top edge of one section and having a top cut-out part at its center, said top edge of said section being cut-away beneath the top of the bracket, a spring catch beneath the bracket top, and a latch secured to the other section and being engageable 75 beneath the top of the bracket and with said catch.

3. In a folding box, hinged side and end sections, one of two adjacent sections having a tongue and the other a groove to receive the tongue, a latch on the section having the tongue extending above the tongue but being spaced from the outer side face of the tongue so that the tongue will, when its section is folded, hold the latch out of 85 contact with any part of the box that the tongue engages with, and a catch on the section having the groove to engage the latch.

4. In a folding box, hinged side and end sections, one of two adjacent sections having a tongue and the other a groove to receive the tongue, a latch on the section having the tongue extending above the tongue but being spaced from the outer side face of the tongue so that the tongue will, when its 90 section is folded, hold the latch out of contact with any part of the box that the tongue engages with, a catch on the section having the groove to engage the latch, and a housing for the catch which projects beyond the 100 latter so as to protect same.

5. In a folding box, hinged side and end sections, an L-shaped latch secured to the outer side face and top edge of one section and having a downturned end which extends 105 on the inner side face of said section, the top edge of the other adjacent section being beveled, a catch secured to said top edge of the other section and being engageable with said downturned latch end, a housing extending over the catch and secured to the second named section, and a tongue on the first named section extending beyond the downturned latch end and being receivable in a groove provided therefor in the second 115 named section.

6. In a folding box, hinged side and end sections, a catch secured to the top edge of one section, a latch disposed on the top edge of the adjacent section and engageable with the latch, a tongue and groove connection between said sections the tongue of which projects beyond the latch and a housing for the catch which projects therebeyond.

7. A folding box including hinged sides 125 and ends, a catch borne by one of said parts,

a latch borne by the other part and being engageable with the catch, and a tongue and groove connection between the adjacent side and end, the tongue extending beyond the latch so that when the parts are folded the tongue will prevent the latch from contacting with any of the parts of the box.

In testimony whereof I have hereunto set my hand in the presence of two subscribing witnesses.

GUSTAV DIECKMANN.
